CENTRIFUGAL BLASTING MACHINE

Chester E. Unger, Mishawaka, Ind., assignor to
 The American Foundry Equipment Company,
 Mishawaka, Ind., a corporation of Delaware

Application December 14, 1939, Serial No. 309,179

16 Claims. (Cl. 51—9)

This invention relates to centrifugal blasting machines, and more particularly to an improved blasting machine capable of centrifugally impelling abrasive at blasting velocities concentrated in the desired work zone.

In the cleaning of metal castings, forgings, large sheets and the like, it is desirable that the thrown abrasive be concentrated not only as to direction but so controlled as to define an impingement pattern of the desired length and breadth through which the abrasive is substantially uniformly distributed. The centrifugal blasting machine forming the subject matter of this invention is designed to attain these desirable ends.

In accordance with this invention, an abrasive throwing rotor is provided which is driven in timed relation to a control runner positioned within the rotor. The rotor comprises generally a rotor head mounted upon a high speed shaft having an abrasive receiving container fixed to rotate thereon. The container is formed of suitable strong wear resistant metal, having a rear wall and a tubular side wall, the interior surface of which provides a support for the abrasive supplied thereto. Abrasive is supplied to the rotor container by means of a control runner positioned therein. The interior of the rotor container is provided with a plurality of spaced ribs or vanes fixed to rotate with the container. The abrasive, driven by centrifugal force outwardly against the interior surface of the tubular side wall of the container, drifts against the ribs or vanes therein provided and is carried around the interior surface of the container during rotation thereof.

The interior surface of the container is provided with uniformly spaced discharge ports in the tubular side wall thereof. When the abrasive caught by the vanes or ribs has piled up to a point where its angle of repose is exceeded, the abrasive will string laterally from each lug or vane, forming a ridge of abrasive between the discharge ports in the container.

The control runner is also provided with an abrasive receiving container having a rear wall and a tubular side wall fixed to a drive shaft which may extend through the hollow shaft of the rotor. The control container is supplied with abrasive by means of a suitable abrasive supply pipe which is fed into the interior thereof. The abrasive is discharged through spaced discharge ports provided in the side wall of the control container during rotation thereof, collects or drifts against the vanes or ribs provided on the

interior surface of the rotor container, and thence strings across the side wall of the rotor container in transversely extending drifts or ridges.

5 An important feature of this invention is the provision of a plurality of scraper vanes which are fixed to rotate with the runner container. The outer ends of these scraper vanes rotate over the strings or ridges of abrasive positioned between the discharge ports of the rotor container and scrape the top portion of each abrasive ridge into the discharge ports of the rotor. The outer ends of the scraper vanes preferably have a broad edge which extends on a bias with respect to the axis of rotation of the control runner. As thus shaped the scraper vanes of the control runner operate to scrape abrasive through the discharge ports in the rotor substantially the full width thereof, thus obtaining an impingement pattern of the desired width. The throwing rotor may be provided with abrasive propelling blades associated with the discharge ports thereof to give the abrasive a positively impelled blasting velocity.

10 The number of scraper vanes provided on the control runner should be either greater or less than, but not equal to, the number of discharge ports provided in the throwing rotor. Where it is desired to obtain directional discharge over one section of the rotor only, the number of scraper vanes provided on the control runner is preferably either one less or one more than the number of blades or discharge passages provided in the throwing rotor.

15 The rotor shaft and runner shaft are operably connected by means of a suitable drive transmission so that a drive ratio between these two shafts is established which is in inverse ratio to the number of scraper vanes provided on the control runner and discharge passages provided in the throwing rotor. Assuming, for example, that the rotor is provided with eight throwing blades or discharge passages and the runner is provided with nine scraper vanes, and assuming further that an effective blasting speed can be attained with this machine when the rotor is rotated at 2250 R. P. M., then the runner should be rotated at 2000 R. P. M. If this inverse ratio is at all times maintained, the scraper vanes in the runner can be moved into position to scrape the abrasive into the discharge passages of the rotor at any predetermined clockdial position, so that the machine will fire the abrasive over a predetermined clockdial sector during rotation thereof. When it is desired to discharge the

abrasive from two diametrically opposed rotor sectors simultaneously, the scraper vanes in the control runner are preferably either two less or two more than the number of discharge passages in the throwing rotor so that the scraper vanes in the control runner and the discharge passages in the throwing rotor will move into discharging alignment at two positions, diametrically spaced. The necessary fixed drive ratio between the rotor shaft and runner shaft can be maintained by positive interconnecting drives between the shafts and rotating both shafts from a common power source. The drive transmission between the rotor shaft and runner shaft may take the form of intermeshing gears, chain and sprocket drive, Morse drive, or any other positive drive mechanism which will maintain the required drive ratio.

The throwing rotor, as well as the control runner, may be made in numerous different shapes and forms within the purview of this invention. The discharge passages in the rotor may comprise discharge ports formed in the relatively thick rotor ring or tubular side wall of the container. The discharge ports should be of sufficient depth to receive the abrasive thereon and forcibly impel the abrasive forwardly during rotation of the machine at blasting velocities, which surfaces may be provided by removable blades. The blades or discharge passages or ports in the rotor may be made of almost any desired radial length and almost any desired number thereof may be provided, ranging from one to sixteen or more. Substantially the only essential criterion that must be followed is that the scraper vanes in the control runner must be either more or less than the number of discharge ports or blades in the throwing rotor and, further, that the runner and rotor must be driven in substantially positive timed relation so that the abrasive scraper vanes in the runner will advance ahead or drop back of the discharge ports or passages in the rotor at a predetermined clockdial position during timed rotation thereof so that the ends of the scraper vanes will pass over the discharge ports in the rotor at the desired predetermined clockdial position to scrape the ridged abrasive thereinto.

Directional control adjustments can be effected by readjusting the position of the runner on its drive shaft, by readjusting the position of the rotor on its drive shaft, by readjusting the sprocket, gears or other positive drive mechanism that operably connect the runner shaft with the rotor shaft.

An object of this invention is to provide a centrifugal blasting machine in which directional firing of the thrown abrasive can be substantially controlled so as to produce a blast pattern on the target of substantially any desired width and length, which pattern is characterized by uniformity in blast over the entire surface thereof.

Other objects and advantages of this invention will become apparent as the disclosure proceeds.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in con-

nection with the accompanying drawings forming a part thereof, in which

Fig. 1 is a transverse cross-sectional view through the abrasive throwing machine, showing the throwing rotor and control runner with drives therefor;

Fig. 2 is a front face view of the throwing rotor and control runner as it appears when looking in the direction of the arrows 2-2 of Fig. 1;

Fig. 2a is an enlarged sectional view through a portion of the throwing rotor taken along line 2a-2a of Fig. 2;

Fig. 3 is a cross-sectional view through the throwing rotor and control runner as it appears when looking in the direction of the arrows 3-3 of Fig. 1;

Fig. 4 is a cross-sectional view showing certain details of the driving mechanism for the throwing rotor and control runner, this view being taken along line 4-4 of Fig. 1;

Fig. 5 is a transverse cross-sectional view through an abrasive throwing machine showing a bladed throwing rotor and control runner of somewhat modified construction; and

Fig. 6 is a cross-sectional view through the throwing rotor and control runner as it appears when looking in the direction of arrows 6-6 of Fig. 5.

Similar reference characters refer to similar parts throughout the several views of the drawings and the specification.

Referring more particularly to Figs. 1 to 4 inclusive, a throwing rotor 10 is illustrated fixed to a hollow shaft 13, rotated by a pulley 60 operably connected to a suitable source of power, as an electric motor, as by a V-belt drive. A control runner 40 mounted upon a shaft 51 extending through hollow shaft 13 is operably connected to be driven in timed relation to shaft 13 and rotor 10. The throwing rotor 10 is provided with a plurality of equally spaced abrasive discharge passageways or ports 27, which are shown for purposes of illustration as eight in number. The control runner 40 is also provided with equally spaced abrasive scraper vanes 48, which should be greater or less in number than the discharge ports 27 in the throwing rotor 10, but shown in Fig. 2, for purposes of illustration only, as nine in number. The speed of rotation of the control runner 40 with respect to the throwing rotor 10 is such that the scraper vanes 48 of the control runner will scrape the ridge or drift of abrasive into the discharge ports 27 of the rotor when the scraper vanes 48 move thereover in the desired clockdial position so as to effect controlled directional firing of the abrasive ejected from the throwing rotor 10.

The throwing rotor 10, as shown in Figs. 1 to 3 inclusive, may comprise a rotor head constructed in the form of a container, having a rear wall 11 and a tubular side wall 12 which may be formed as a single casting from a suitable tough wear resistant metal. The rear wall 11 of the container may be provided with a central opening 16 which receives the closed end of another tubular container 41 which forms a part of the control runner 40. The rear wall 11 of the throwing rotor 10 is fixed to a hollow shaft 13 by means of a hub member 14 which is fixed to the shaft 13 by means of a spline or set screw 65 and which is also fixed to the rear wall 11 of the container rotor 10 by suitable bolts 15. The interior of the rotor container 10 may be provided with an abrasive resistant lining, if desired, comprising a rear wall forming surface 17 which

lines the rear wall 11 of the container 10 and a side wall lining surface 23 which lines the inside face of the tubular side wall 12 of the container 10. The interior side wall surface 23 of the container 10 is preferably of substantial depth, the inner half of which is provided with a plurality of spaced vanes 22, equal in number to the discharge ports 27. The vanes or lugs 22 are fixed to rotate with the rotor container 10, and each vane 22 may be provided with a rearwardly curved advancing surface 24 formed of wear resistant material, which forms a V-shaped abrasive receiving pocket 25 with the liner wall 23. Abrasive flowing over the advancing surface 24 of each vane 22 lodges in the pockets 25 where the abrasive attains the peripheral velocity of the rotating pockets 25. When sufficient abrasive has collected in each of the pockets 25, some of the abrasive will roll out of the pockets and collect in the form of a ridge on the inclined surface 26 of the container 10.

It will be noted that drift forming vanes 22 equal in number to the discharge ports 27 are provided. Each vane 22 has its lower pocket forming end positioned approximately midway between adjacent spaced openings 27 so that the abrasive put in motion by each vane 22 will roll in the form of a drift between adjacent spaced discharge ports 27 where the drift will normally cling to the inner surface 26 of the container. An abutment member 20 positioned adjacent the outer free edge of the container side wall 12 may be provided to prevent abrasive from spilling over the free edge of the container side wall. The abutment member 20 may be in the form of a ring having a central opening through which the discharge end of the abrasive supply conduit 45 extends, the ring seating within a pocket 21 and held in position thereby.

The control runner 40 provides means for supplying abrasive to the drift forming vanes 22 of the rotor container 10 and for scraping the drifted abrasive into the discharge ports 27 of the rotor 10 during a predetermined selected clockdial sector of rotation thereof whereby the abrasive thrown by the rotor 10 is directionally controlled. An abrasive supply container 41 having a tubular side wall 42 and a rear wall 43 extends into the rotor container 10 and is fixedly secured to the end of runner drive shaft 51. The runner drive shaft 51 may be provided with a square or rectangular boss 52 at one end thereof which extends through a square opening 53 in the rear wall 43 of the feeding container 41. A clamping plate 54 which bears against the inside face of the rear wall 43 of the feeding container 41 receives a lock bolt 55 which screws into the threaded end of the boss 52 of shaft 51, thus fixedly securing the feeding container 41 thereto.

Abrasive is supplied to the feed container 41 by means of a feed pipe 45 having the discharge end 46 thereof arranged to deposit abrasive into the rotatably mounted feed container 41. The feed container 41 may be provided with an in-turned lip 44 which surrounds the discharge end 46 of the feed pipe to prevent leakage of abrasive therefrom. The feed pipe 45 may also be provided with a circumferential flange 47 which overlaps the in-turned lip portion 44 of the feeding container 41. It will be appreciated that the feeding container 41 must be free to rotate without interference with the feed pipe 45, sufficient clearance between adjacent stationary and rotating parts being accordingly provided.

The abrasive *a* rolls down the feed pipe 45 and into the feeding container 41 where it clings in the form of a blanket around the interior face of the tubular side wall 42 thereof. A plurality of spaced discharge ports 46' is provided in the tubular side wall 42 of the feeding container 41, through which the abrasive is discharged into the path of rotation of the drift forming vanes or lugs 22. Preferably the inner ends of the vanes 22 extend close to the outer periphery of the tubular side wall 42 of the feeding container 41. Discharge ports 46', equal in number to the drift forming vanes 22, are preferably provided. The discharge ports 46' preferably have an axial width less than the width of the drift forming vanes 22 and are positioned adjacent the inner ends thereof. The abrasive discharges from the discharge ports 46' in all clockdial directions and passes onto the advancing face 24 of the drift forming vanes 22. The abrasive passing onto the advancing face 24 of the drift forming vanes 22 may be confined thereon between the rear wear surface 17 and a circular side wall member 31 fixed to the vanes 22. The side wall member 31 has a central opening 32 provided therein into which the feeding container 41 projects. The outer periphery 33 of the circular plate 31 terminates short of the side wall liner 23 to permit lateral drift of the abrasive thereunder. The side wall member 31 may be integrally formed with the drift forming vanes 22 or may be bolted or otherwise secured to the rear wall 11 of the rotor. The circular side wall plate 31 serves to retain the abrasive on the advancing face 24 of the drift forming vanes 22, guiding the abrasive into the pockets 25.

The control runner 40 is provided with a plurality of equally spaced scraper vanes 48 which extend laterally from and may be integrally formed with the tubular side wall 42 of the feeding container. The scraper vanes 48 are forwardly inclined with respect to the direction of rotation of the rotor, as shown more particularly in Fig. 2, when the control runner 40 is provided with a greater number of scraper vanes 48 than discharge passages 27 in the rotor. If the control runner 40 is provided with a less number of scraper vanes 48 than the number of discharge passages 27 in the throwing rotor 10, the vanes 48 would then be inclined rearwardly with respect to the direction of rotation thereof. In the embodiment illustrated in the drawings, the control runner 40 as shown is provided with nine scraper vanes 48 while the throwing rotor 10 is provided with eight discharge ports 27. It will also be noted that the lower end 49 of each of the scraper vanes 48 is positioned closely adjacent the inside surface 26 of the tubular wall 12 of the rotor 10 and has its outer end 57 biased with respect to the axis of rotation of the control runner.

To guide the abrasive over the inclined surface 26 in a well defined ridge or string, one or more abrasive retaining grooves 26', as shown in Figs. 2 and 2a, may be provided for each drift forming vane. These grooves preferably extend on a bias and approximately parallel to the biased ends 49 of the scraper vanes 48. The grooves 26' provide a firm grip for the abrasive so that the abrasive will pile up thereover in a well defined ridge which will be engaged by the lower ends 49 of the scraper vanes 48 during operation.

The hollow rotor supporting shaft 13 extends into the hub 14 and is supported by a pair of suitable spaced brackets 66 and 67 each having one or more ball bearing mountings for the shaft 13,

each comprising raceway collars 68 fixed to the shaft 13, raceway collars 69 carried by its supporting bracket, and ball bearings 70 which move in the raceway collars 68 and 69. Rotor shaft 13 is driven by means of a suitable V-belt drive trained over the pulley wheel 60 fixed to the shaft 13 as by set screw 61.

The inner end of runner shaft 51 is rotatably supported within the hollow shaft 13 by means of a suitable bearing comprising raceway collar 71 fixed to the hollow interior of shaft 13 and raceway collar 72 fixed to shaft 51, raceway collars 71 and 72 having ball bearings 73 rollable therebetween. The opposite end of shaft 51 may be likewise supported by a suitable bearing comprising raceway collar 74 fixed to the interior of hollow shaft 13 and raceway collar 75 fixed to the runner shaft 51 with roller bearings 76 in position to roll between these raceway collars.

Means are provided for operably connecting rotor shaft 13 to runner shaft 51 so that they can be driven in the proper timed relationship. As shown more particularly in Figs. 1 and 4, a driving gear 77 is fixed to the end of rotor shaft 13, which driving gear meshes with a plurality of transfer gears 78 each fixed to a spindle shaft 79. Each spindle shaft 79 is free to rotate in suitable bush bearings 80 and 81 provided respectively in a gear casing 82 and a gear casing closure cover 83. A second transfer gear 84 is also fixed to each spindle shaft 79, each arranged to mesh with a gear 85 fixed to the end of runner shaft 51. The gear housing 82 may be provided with a suitable collar 86 by means of which it may be secured as by set screw 87 to a circular flange 88 provided on the adjacent shaft supporting bracket 61. The gear housing enclosing cover 83 may be removably secured to the gear housing 82 by means of suitable lag screws or bolts 89, giving free access to the train of gears therein. Thus the driving mechanism for rotor shaft 13 and runner shaft 51 is completely enclosed, and grease or lubricating oil in the space 90 within the hollow shaft 13 and the space 91 within the gear box casing 82 is kept in constant agitation by the moving parts to lubricate the gears and shaft supporting bearings therein.

It will be appreciated that when the throwing rotor 10, equipped with eight discharge ports 27, as shown in Figs. 1, 2 and 3, is rotated at 2250 R. P. M. and the control runner 40, equipped with nine discharge scraper vanes 48, is rotated at 2000 R. P. M., the scraper vanes 48 will move over the discharge ports 27 at a predetermined clockdial position, so as to permit discharge of the abrasive in a controlled direction. The advancing faces 27' of the rotor passages 27 operate to throw the abrasive approximately tangentially from the periphery of the rotating throwing rotor. This feed differential may be obtained by making the gears 77 and 85, which drive the rotor shaft 13 and runner shaft 51, of the proper relative tooth ratio to effect this result. Since the speed differential between the control runner 40 and the throwing rotor 10, in the machine disclosed in Figs. 1 to 3 inclusive, may be only 250 R. P. M., no serious wear on the adjacent faces of the moving parts of the control runner 40 and throwing rotor 10 results.

When the machine shown in Figs. 1 to 3 inclusive is brought up to speed, with the throwing rotor 10 rotating at 2250 R. P. M. and the control runner 40 rotating at 2000 R. P. M., abrasive is supplied to the interior of the feeding container 41. The initial abrasive supplied to the

feeding container 41 clings to the interior surface of the tubular side wall 42 therecf, and as more abrasive is supplied thereto this additional abrasive rolls over the top of the initial abrasive first supplied and discharges out through the peripherally arranged discharge ports 48'. The abrasive discharging from the ports 48' moves radially outward between the drift forming vanes 22 of the throwing rotor 10, comes into contact with the advancing face 24 of the throwing vanes 22 and lodges in the V-shaped pockets 25 formed by the rearwardly inclined vanes 22 and the inside surface 23 of the rotor container. As additional abrasive is supplied to the pockets 25, the additional abrasive drifts to the right in the structure shown in Figs. 1 and 2 and rolls onto the inclined surface 26 of the rotor container. Since the abrasive discharging laterally from the drift forming vanes 22 has already achieved a peripheral velocity substantially equal to the rotating velocity of the inner surface 23 of the rotor container, this abrasive continues to cling to the inclined surface 26 of the rotor container and piles up in a ridge or drift between adjacent discharge passages 27. This drifting abrasive when undisturbed will substantially maintain its drifted position unless excessive quantities of abrasive is fed thereto, because of the grooves 26' or intermediate ribs 26''.

It will be noted that the control runner 40 rotates in the same direction as the throwing rotor 10 but at a predetermined lesser velocity. Since the control runner 40 is provided with nine scraper vanes 48 and is driven in timed relationship to the throwing rotor 10, as above indicated, the discharge passages 27 of the throwing rotor 10 will advance under the ends 49 of the scraper vanes 48 at a predetermined clockdial position, depending upon the setting of the control runner 40 with respect to the throwing rotor 10. Each ridge of abrasive streaking from each drift forming vane 22 laterally across the inclined surface 26 of the rotor container is engaged by the rear face 49' of each scraper vane 48, which abrasive is scraped into the discharge passages 27 advancing under it. The free ends 49 of the scraper vanes 48 are arranged on a bias, as shown in Fig. 2, so that abrasive is discharged from the full axial width of the discharge ports 27 so that uniform distribution of the discharged abrasive is obtained. An impingement pattern of any desired length may be obtained dependent upon the peripheral length of the discharge ports 27 in the rotor container.

The discharge ports 27 may be lined or covered by means of a wear resisting liner 27' which may be made in the form of a tube. The liners 27' may be removably held in fixed position by a pair of metal bands 27'' which overlap the lower end of the wear members 27', as shown in Fig. 1, and which bands may be held in place by spaced screws 27'''. The ring member 20 may be made sectional in form, as shown in Fig. 1, and may be so formed as to overlap the inturned flange 41 on the feed pipe so as to provide a substantially enclosed chamber within the rotor head 10, thus appreciably lessening the effect of air currents.

The baffle member 20 fixed to the rotor container prevents leakage of abrasive over the outer rim of the rotor container. If desired, the baffle member 20 may extend substantially to the outer periphery of the feed pipe 45 and to a position to substantially overlap the flange portion 41 of the feed pipe 45, thus lessening the effect of distributing air currents within the rotor 10. The

throwing faces 27' of the discharge ports 27 can be of any desired length and the feeding container 41 and the rotor container may also be of any desired diameter.

A centrifugal abrasive blasting machine constructed in accordance with this invention may take other forms than that shown in Figs. 1 to 3 inclusive. For example, there is shown in Figs. 5 and 6, a centrifugal blasting machine of somewhat modified construction, comprising a throwing rotor 100 having a control runner 150 associated therewith. The throwing rotor 100 may comprise a side wall member 101 and a side wall member 102 spaced therefrom and extending generally parallel to side wall member 101, which side wall members may be connected by suitable spacers 103 having their reduced ends 104 welded or otherwise secured to the side wall members. Equally spaced radially extending blades *b* are removably mounted between the spaced side wall members 101 and 102, each blade comprising a bottom wall portion 106 and side flange portions 107 which seat within suitable paired grooves 105 provided on the inside face of the side wall members 101 and 102. Each blade *b* may be removably secured in operative position by means of a suitable set screw 135 having a tapered end which seats within a corresponding tapered recess provided in the side edge of each blade *b*. Each set screw 135 may be screwed into a suitable threaded aperture provided in the side wall member through which it extends.

The side wall members 101 and 102 are each provided with a circular opening whose peripheral inner edges 108 and 109 respectively are substantially in alignment with the inner ends of blades *b*. A tubular sleeve member 120 which forms the rotor container extends into the aligned circular openings in the front and rear side wall members 101 and 102, respectively, and is provided with an outturned flange portion 123 which may be secured as by screws 124 to the front side wall members 102 so as to rotate with the blades *b*. The tubular sleeve member 120 is provided with a tubular side wall 121 and a rear wall 122 which seats within a suitable circular cavity 115 in the hub 110. The collar portion 111 of the hub 110 is provided with a circular opening into which the hollow tubular drive shaft 13 extends, the hub 110 being secured to the drive shaft 13 by means of a suitable spline 112. The hub 110 is provided with a securing flange 113 which seats against the side wall member 101 and is secured thereto by means of suitable bolts 114. The tubular side wall 121 of the tubular sleeve member 120 is provided with a plurality of discharge openings 125, each positioned adjacent the advancing face of a blade *b*, the opening 125 having an axial width extending between the side flanges 107 of its corresponding blade *b*.

The tubular sleeve member 120 is provided also with a plurality of spaced, rearwardly inclined vanes 128 positioned rearwardly of the discharge ports 125. Each vane 128 forms with the inner surface 126 of the tubular sleeve member 120 an abrasive receiving pocket 127. Each pocket 127 provides a place into which the abrasive supplied by the tubular sleeve member 120 may drift, the outer end 129 of each vane 128 being secured to the inner surface 126 of the tubular sleeve member 120. The outer end 129 of each vane 128 is located approximately equidistantly between the adjacent spaced discharge ports 125 but rearwardly thereof. It will be noted that the drift forming vanes 128 are equal in number to the dis-

charge ports 125, eight drift forming vanes 128 and eight discharge ports 125 being illustrated in Figs. 5 and 6. A circular abutment member 133 fixed to the tubular side wall 121 of the tubular sleeve member 120 retains the abrasive within the sleeve member 120.

A control runner 150 is positioned within the tubular sleeve member 120, as shown in Figs. 5 and 6. The control runner 150 comprises a tubular feed container 151 having a tubular side wall 152 which extends centrally into the tubular sleeve member 120. The rear wall 122 of the tubular sleeve member 120 has a circular opening 134 provided centrally therein to receive the rear end of the feed container 151. The feed container 151 is provided with a rear wall 153 which has a square opening 155 therein into which the squared end 154 of the control runner drive shaft 51 extends. A top plate 156 overlaps the inside face of the rear wall 122. A threaded bolt 157 which extends through the top plate 156 is screwed into the squared end 154 of the drive shaft 51 to rigidly hold the feed container 151 to its drive shaft 13.

Abrasive is supplied to feed container 151 by an abrasive supply pipe 160 whose discharge end 161 may extend into a circular opening 158 defined by an inturned lip portion 159 provided on the front end of the side wall 152 of the feed container 151. The feed pipe 160 is provided with an outturned flange portion 162 which overlaps the inturned lip portion 159 of the feed container 151, and, if desired, a secondary flange 163 may be provided on the feed pipe 160 which overlaps the abutment member 133 provided on the rotor container so as to lessen the effect of disturbing air currents therein. To prevent clogging of the feed pipe 160, an aperture 164 may be provided in its lower belly adjacent the discharge end for admission of air into the lower end of the feed pipe which insures free flow of abrasive therethrough. Leakage of abrasive through the air inlet port 164 of the feed pipe is prevented by a shelf 165 which overhangs the opening 164.

When the machine has been brought up to speed, abrasive is supplied to the feed container 151 by the abrasive supply pipe 160, which abrasive is thrown by centrifugal force against the inside surface thereof. The abrasive works rearwardly of the feed container 151 and flows out through the discharge ports 125 in the tubular side wall thereof and then into the path of rotation of the drift forming vanes 128. The abrasive flows over the advancing faces of the vanes 128 into the abrasive receiving pockets 127. As each pocket 127 is supplied with an increasing quantity of abrasive, the excess abrasive will streak or thread across the inner surface 127' of the feed container in the form of a ridge or pile of abrasive. Each ridge or pile of abrasive will be deposited between adjacent discharge ports 125 in the tubular sleeve member 120.

The control runner 150 is provided with a plurality of equally spaced scraper vanes 171 which extend from the side wall 152 of the feed container 151 to a point closely adjacent the inside surface 127' of the tubular sleeve member 120. It will be noted in the structure shown in Figs. 5 and 6 that nine scraper vanes 171 are supplied which should incline forwardly with respect to the direction of rotation thereof. The scraper vanes 171 may be formed of wear resistant material and may be integrally formed with a tubular side wall 152 of the feed container 151.

The tubular drive shaft 13 of the throwing

rotor 100 is driven in timed relation to the drive shaft 51 of the control runner by drive mechanism which may be of the type illustrated more particularly in Fig. 1. If desired, an oil seal may be provided comprising a gasket 181 which surrounds the inner end of the shaft 51, which gasket 181 is contained in a channel-shaped receiver 180 fixed to the interior of the hollow shaft 13. The gasket 181 prevents lubricating oil from escaping from the interior of the hollow shaft 13.

The centrifugal abrasive throwing machine as illustrated in Figs. 5 and 6 is designed to rotate clockwise. Since the throwing rotor 100 illustrated is equipped with eight throwing blades *b*, each having an associated discharge port 125, and the control runner 150 is equipped with nine scraper vanes 171 rotating within the sleeve member 120 of the rotor 100, the rotor 100 and runner 150 should be driven in the drive ratio of nine to eight. For example, assuming that the throwing rotor 100 has a blade tip diameter sufficient to develop the desired abrasive blast when rotating at 2250 R. P. M., the control runner 150 including the scraper vanes 171 would then be rotated at approximately 2000 R. P. M. This drive ratio may be maintained as heretofore explained by providing the drive shafts 13 and 51 within a connected driving gear having the proper drive ratio. The abrasive supplied to the feed container 151 is thrown by centrifugal force out through the spaced discharge ports 125 thereof into the path of rotation of the vanes 128 and thence into the abrasive receiving pockets 127 from which the abrasive rolls across the inclined interior surface 127' of the tubular sleeve member 120 while resting on this interior surface, to form spaced ridges or piles of abrasive. While the scraper vanes 171 rotate in the same direction of rotation as the port openings 125 and the throwing blades *b*, they rotate at less velocity as above indicated, so that the rear surface of each scraper vane 171 will drag over the discharge ports 125 in a predetermined clockdial position of rotation of the throwing rotor 100, causing the abrasive to discharge from the discharge ports 125 onto the throwing blades *b* from which it is thrown at an abrading velocity. The lower end 172 of each scraper vane 171 is positioned closely adjacent the inside surface 127' of the tubular sleeve member 120 and is further inclined on a bias so as to scrape abrasive into the discharge port 125 over substantially the full axial width of the discharge port 125.

Adjustments can be made so that the abrasive discharged from the throwing rotor 100 will be fired in any desired clockdial direction. This is effected by proper rotative adjustment of the discharge passages 125 in the rotor container 120 with respect to the scraper vanes 171 associated with the control runner 150. This discharge adjustment can be advantageously effected by resetting the gear 85 in the gear box 82.

It will be appreciated that the throwing rotor may be made in any desired diameter and may be rotated at any desired speed, the control runner being rotated at a corresponding speed ratio determined by the relative number of discharge passageways or blades in the rotor with respect to the scraper vanes on the runner. The rotor and runner are rotated at speeds which are in inverse ratio to the number of their discharge ports and scraper vanes respectively, so that each runner port will be traversed by a scraper vane at the same clockdial position during rotation. The scraper vanes of the runner and the rotor

ports can be so adjusted that abrasive is scraped into the discharge ports of the runner at any desired clockdial position during rotation, by merely adjusting the position of the scraper vanes with respect to the discharge ports of the rotor.

It will be further appreciated that in the several illustrated embodiments of this invention, the throwing rotor may be provided with any desired number of throwing blades or discharge ports, and a high degree of directional control can be continuously maintained by providing a control runner having either a greater or lesser number of scraper vanes, preferably providing the control runner with either one more or one less scraper vane than abrasive discharge ports provided in the throwing rotor, if abrasive firing from a single selected clockdial position is desired. The abrasive may be fired from an abrasive rotor in any desired clockdial direction by a proper mathematical adjustment of the control runner with respect to the throwing rotor.

Assuming, for example, that a throwing rotor is provided with eight equally spaced discharge passages or blades and the control runner is provided with nine equally spaced scraper vanes, as shown in Figs. 5 and 6, and that it is desired to shift the direction of discharge from a normally downward or six o'clock position to a normally sideways or three o'clock position, with the rotor and runner rotating clockwise. This control adjustment can be effected by rotating the control runner 150, as shown in Figs. 5 and 6, so as to bring one of the scraper vanes 171 thereof into a position whereby it would scrape abrasive into one of the discharge ports 125 of the tubular sleeve member of the rotor, at approximately the nine o'clock position. This would require rotation of the control runner 150 a distance of approximately 10° counterclockwise from its position shown in Figs. 5 and 6 where the runner and rotor parts are shown in position to discharge abrasive through a discharge port 125 at the twelve o'clock position. This assumes, of course, that the rotor blades are of such length that when the abrasive is moved out to the inner ends thereof at approximately the nine o'clock position, it will discharge at approximately the three o'clock position. The arc through which the abrasive is carried by the rotor blades after being received on the inner ends thereof and before being discharged therefrom, obviously depends upon various conditions, such as the radial length of the rotor blades and the smoothness of the throwing surfaces thereof. The number of degrees that the control runner should be rotated to effect the desired directional discharge can generally be computed to a mathematical certainty, but the proper adjustment can most readily be determined in actual practice by trial and thereafter from resulting experience with a particular machine.

It may at times be desired to clean castings, forgings, bars and sheets which are positioned on opposite sides of the throwing rotor. My improved centrifugal abrasive throwing machine may be constructed and designed to accomplish this result by providing the machine with a control runner having equally spaced abrasive scraper vanes or passages either two more or two less in number than the abrasive discharge ports in the throwing rotor. The control runner and throwing rotor are then rotated in timed relation so that two opposite scraper vanes in the control runner will scrape over two opposite discharge

ports in the throwing rotor at opposed clockdial positions during rotation thereof.

Thus it will be appreciated that accurate and controlled firing in one direction only or in two or more predetermined directions from the same machine can be obtained by providing the control runner and throwing rotor with a proper number of scraper vanes and discharge ports and rotating the runner and rotor at speeds which are in inverse ratio to the number of scraper vanes and discharge ports therein. Upblast or downblast, or both upblast and downblast, a three o'clock side blast or a nine o'clock side blast or both a three o'clock and a nine o'clock side blast, may be obtained with a machine constructed as above described.

The throwing rotor may be of any desired diameter, preferably ranging from nine to thirty inches, and the throwing blades or passages of the throwing rotor may be of any desired radial length and, if desired, may be of such length as to extend close to the axis of rotation, providing only a sufficient central opening in the rotor to make room for the control runner positioned therein. When the blades of the throwing rotor are of substantial length, it is obvious that wear on the control runner and the rotor sleeve may be correspondingly reduced, with greater wear concentrated on the throwing blades of the rotor, which may be made removable and replaceable. If the throwing blades of the throwing rotor are of relatively short radial length with a corresponding increase in diametric size of the control runner, the control runner and particularly the scraper vanes thereof will then receive some wear, and these vanes may be made removable and replaceable as is obvious to those skilled in the art.

The abrasive receives its final abrading velocity from the advancing faces of the rotor blades or throwing surfaces thereof, which are preferably made removable so that these parts can be replaced when worn. The parts of the machine which receive tensile strains and shocks may be made of a high grade steel, and the parts subjected to wear may be made of a suitable wear resisting metal.

One of the marked advantages of this machine is that an impingement pattern of almost any desired width may be obtained. This desirable result is accomplished by reason of the fact that the scraper vanes of the control runner are arranged on a bias so that abrasive is scraped over substantially the entire width of the discharge ports in the throwing rotor. A substantially uniform concentration of the abrasive is obtained throughout the impingement pattern. The longitudinal length of the impingement pattern may be regulated as desired by varying the peripheral length of the discharge ports in the throwing rotor. A highly satisfactory degree of directional firing of the thrown abrasive may be obtained, and the impingement pattern nicely defined both as to its length and its breadth. The abrasive is distributed uniformly over substantially the entire width of the rotor blades, producing more uniform wear on each of these parts with a resulting full width impingement pattern on the target. The length of the impingement pattern on the target can be easily fixed and determined by varying the peripheral length of the discharge ports in the throwing rotor.

It is understood that where the term "abrasive" is herein used, it is intended to refer to steel shot or grit, quartz sand, or other granular material

commonly used in the blast cleaning of castings, forgings, bars, sheets and like metallic materials, to remove encrusted molding sand, irregular projections and scale from the surface thereof.

5 While certain novel features of the invention have been disclosed and are pointed out in the annexed claims, it will be understood that various omissions, substitutions and changes may be made by those skilled in the art without departing from the spirit of the invention.

10 What is claimed is:

15 1. A centrifugal abrasive blasting machine operable to throw a concentrated stream of abrasive over a predetermined limited arc including, a rotatably mounted rotor having a plurality of equally spaced abrasive discharge passages whose inner ends are separated by arcuate shaped abrasive receiving surfaces facing inwardly and spaced from the axis of rotation thereof whereby said surfaces define a central space, means for depositing abrasive on said arcuate surfaces, a rotatably mounted control runner positioned within said central space having a plurality of equally spaced abrasive scraper vanes differing in number from the number of discharge passages in said rotor, the outer ends of said scraper vanes being positioned to engage the abrasive on said arcuate surfaces during rotation of said runner, and driving means operable to rotate said rotor and runner in timed relation and at speeds which are in inverse ratio to the number of discharge passages and abrasive scraper vanes in said rotor and runner respectively so as to move the abrasive engaged by the successive vanes in said runner into abrasive discharging position with respect to the successive passages in said rotor at a predetermined clockdial position during rotation.

20 2. A centrifugal abrasive blasting machine operable to throw a concentrated stream of abrasive over a predetermined limited arc including, a rotatably mounted rotor having a plurality of equally spaced abrasive discharge passages whose inner ends are separated by arcuate-shaped abrasive receiving surfaces facing inwardly and spaced from the axis of rotation thereof whereby said surfaces define a central space, means for depositing abrasive on said arcuate surfaces, a rotatably mounted control runner positioned within said central space having a plurality of equally spaced abrasive scraping means differing in number from the number of discharge passages in the throwing rotor, the outer ends of said scraping means being positioned to engage the abrasive on said arcuate surfaces during rotation of said runner, and means for rotating said rotor and runner in timed relation and at speeds which are in inverse ratio to the number of discharge passages and abrasive scraping means in said rotor and runner respectively so as to move the successive means of said runner into abrasive discharging position with respect to the successive passages of said rotor at a predetermined clockdial position during rotation.

25 3. A centrifugal abrasive blasting machine operable to throw a concentrated stream of abrasive over a predetermined limited arc including, a rotatably mounted rotor including a generally tubular-shaped wall having a plurality of equally spaced abrasive discharge passages therein which are separated by arcuate-shaped abrasive receiving surfaces facing inwardly and spaced from the axis of rotation thereof whereby said surfaces define a central space, means for depositing abrasive on said arcuate surfaces, a rotatably

mounted control runner positioned within said central space having a plurality of equally spaced abrasive moving vanes differing in number by one from the number of discharge passages in the throwing rotor, the outer ends of said vanes being positioned to engage the abrasive on said arcuate surfaces during rotation of said runner, and means for rotating said rotor and runner in timed relationship and at speeds which are in inverse ratio to the number of discharge passages and abrasive moving vanes in said rotor and runner respectively so as to move the successive vanes of said runner into abrasive discharging position with respect to the successive passages of said rotor at a predetermined clockdial position during rotation.

4. A centrifugal abrasive blasting machine operable to throw two oppositely directed concentrated streams of abrasive each discharged over a predetermined limited arc including, a rotatably mounted rotor having a plurality of equally spaced abrasive discharge passages whose inner ends are separated by arcuate-shaped abrasive receiving surfaces facing inwardly and spaced from the axis of rotation thereof defining a central space, means for depositing abrasive on said arcuate surfaces, a rotatably mounted control runner positioned within said central space having a plurality of equally spaced abrasive moving vanes differing in number by two from the number of discharge passages in the throwing rotor, the outer ends of said vanes being positioned to engage the abrasive on said arcuate surfaces during rotation of said runner, and means for rotating said rotor and runner in timed relation and at speeds which are in inverse ratio to the number of discharge passages and vanes in said rotor and runner respectively so as to move the successive vanes of said runner into opposite abrasive discharging positions with respect to the successive passages of said rotor at predetermined opposite clockdial positions during rotation.

5. A centrifugal abrasive blasting machine operable to throw a concentrated stream of abrasive over a predetermined limited arc including, a rotatably mounted rotor having a plurality of equally spaced abrasive discharge passages which are separated by inwardly facing arcuate-shaped abrasive receiving surfaces, means for depositing abrasive on said arcuate surfaces, a rotatably mounted control runner having a plurality of equally spaced abrasive moving vanes differing in number from the discharge passages of the throwing rotor, said runner having its axis of rotation concentric with the axis of rotation of said rotor with the outer ends of the abrasive moving vanes of the runner positioned adjacent the inner ends of but diagonally arranged with respect to the passages in the rotor, the outer ends of said vanes being positioned to engage the abrasive on said arcuate surfaces during rotation of said runner, and driving means operable to rotate said rotor and runner in timed relation and at speeds which are in inverse ratio to the number of discharge passages and abrasive moving vanes in said rotor and runner respectively so as to move the discharge ends of the abrasive moving vanes of said runner into abrasive ejecting position with respect to the inner ends of the successive passages in said rotor at a predetermined clockdial position during rotation.

6. A centrifugal blasting machine operable to throw a concentrated stream of abrasive over a predetermined limited arc including, a rotor comprising a rotatably mounted side wall member

having a plurality of throwing elements supported by said side wall member, each of said throwing elements having an abrasive discharge port adjacent the inner end thereof which ports are separated by inwardly facing arcuate-shaped abrasive receiving surfaces, a control runner comprising a rotatably mounted tubular member having openings therein through which abrasive is supplied to said arcuate surfaces, a plurality of equally spaced vanes fixed to rotate with said tubular member, and differing in number from the discharge ports in said rotor, means for supplying abrasive to the tubular member of said runner, and driving means operable to rotate said rotor and runner in timed relation and at speeds which are in inverse ratio to the number of discharge ports and abrasive moving vanes in said rotor and runner respectively so as to move the vanes of said runner into abrasive discharging position with respect to said rotor ports at a predetermined clockdial position during rotation.

7. A centrifugal blasting machine operable to throw a concentrated stream of abrasive over a predetermined limited arc including, a rotor comprising a rotatably mounted side wall member and an overhanging rim supported by said side wall member having equally spaced discharge ports therein, a control runner fitting within said rim comprising a plurality of equally spaced abrasive moving vanes whose axis of rotation is concentric with the axis of rotation of said rotor, said runner vanes differing in number from the discharge ports in said rotor rim, means for supplying abrasive to the inner surface of said overhanging rim, and means for rotating said rotor and runner in timed relation and at speeds which are in inverse ratio to the number of discharge ports and vanes in said rotor and runner respectively so as to move the successive vanes of said runner into abrasive discharging position with respect to the successive discharge ports of said rotor at a predetermined clockdial position during rotation.

8. A centrifugal blasting machine operable to throw a concentrated stream of abrasive over a predetermined limited arc including, a rotatably mounted shaft, a rotor supported on said shaft, said rotor having equally spaced abrasive discharge passages separated by inwardly facing arcuate-shaped abrasive receiving surfaces, means for depositing abrasive on said arcuate surfaces, a second shaft having its axis of rotation substantially concentric with the axis of rotation of said first shaft, a control runner mounted on said second shaft having equally spaced abrasive moving vanes differing in number from the number of discharge passages in said rotor, the outer ends of said vanes being positioned to engage the abrasive on said arcuate surfaces during rotation of said runner, and driving mechanism operably connected to said shafts whereby said rotor and runner can be rotated in timed relation and at speeds which are in inverse ratio to the number of discharge passages and vanes in said rotor and runner respectively so as to move the successive vanes of said runner into abrasive discharging position with respect to the successive passages of said rotor at a predetermined clockdial position during rotation.

9. A centrifugal abrasive blasting machine operable to throw a concentrated stream of abrasive over a predetermined limited arc including, a rotor having equally spaced abrasive discharge passages separated by inwardly facing arcuate-shaped abrasive receiving surfaces spaced from

the axis of rotation thereof whereby said surfaces define a central space, means for depositing abrasive on said arcuate surfaces, a rotatably mounted shaft fixed to said rotor, a control runner positioned within said central space having equally spaced abrasive moving vanes therein differing in number from the number of discharge passages in said rotor, the outer ends of said vanes being positioned to engage the abrasive on said arcuate surfaces during rotation of said runner, a second rotatably mounted shaft fixed to said runner having its axis of rotation concentric with the axis of rotation of said rotor shaft, a drive pulley adapted to be connected to a power source, and mechanism operably connecting said pulley to said shafts whereby said shafts may be rotated in timed relation and at speeds which are in inverse ratio to the number of discharge passages and abrasive moving vanes in said rotor and runner respectively so as to move the successive vanes of said runner into discharging alignment with successive passages in said rotor at a predetermined clockdial position during rotation.

10. A centrifugal abrasive blasting machine operable to throw two oppositely directed concentrated streams of abrasive each discharging over a predetermined limited arc including, a rotatably mounted rotor having an even number of equally spaced abrasive discharge passages therein separated by inwardly facing arcuate-shaped abrasive receiving surfaces spaced from the axis of rotation thereof whereby said surfaces define a central space, means for depositing abrasive on said arcuate surfaces, a rotatably mounted control runner positioned within said central space having an even number of equally spaced abrasive moving vanes two less in number than the number of discharge passages in the throwing rotor, the inner ends of said vanes being positioned to engage the abrasive on said arcuate surfaces during rotation of said runner, and means for rotating said rotor and runner in timed relation and at speeds which are in inverse ratio to the number of discharge passages and vanes in said rotor and runner respectively so as to move the successive vanes of said runner into opposite abrasive discharging positions with respect to the successive passages of said rotor at predetermined opposite clockdial positions during rotation.

11. A centrifugal abrasive blasting machine operative to throw a concentrated stream of abrasive over a predetermined limited arc including, a rotatably mounted rotor having a plurality of equally spaced circumferentially extending segments presenting inwardly facing arcuate-shaped abrasive receiving surfaces and defining abrasive discharge passages therebetween, means for depositing abrasive on said arcuate surfaces, a rotatably mounted runner having a plurality of equally spaced radially extending abrasive moving vanes differing in number from the number of discharge passages in said rotor, said runner having its axis of rotation concentric with the axis of rotation of said rotor with the outer end of the abrasive moving vanes of the runner positioned adjacent the inner ends of the discharge passages in the rotor, and driving means operable to rotate said rotor and runner in timed relation and at speeds which are in inverse ratio to the number of discharge passages and abrasive moving vanes in said rotor and runner respectively so as to move the outer ends of said runner vanes into discharging alignment with the successive

passages in said rotor at a predetermined clockdial position during rotation.

12. A centrifugal abrasive blasting machine operable to throw a concentrated stream of abrasive over a predetermined limited arc including, a rotatably mounted rotor having a plurality of equally spaced circumferentially extending segments defining abrasive discharge passages therebetween, a rotatably mounted runner having a plurality of equally spaced radiating vanes differing in number from the number of discharge passages in said rotor, said runner having its axis of rotation concentric with the axis of rotation of said rotor, with the outer ends of its vanes positioned adjacent the inner ends of the passages in the rotor, means for depositing abrasive on the inner facing surface of said segments and between each pair of adjacent abrasive discharge passages defined by said segments, and driving means operable to rotate said rotor and runner in timed relation and at speeds which are in inverse ratio to the number of discharge passages and vanes in said rotor and runner respectively so as to move the outer ends of successive runner vanes into discharging alignment with successive rotor passages at a predetermined clockdial position during rotation.

13. A centrifugal blasting machine operable to throw a concentrated stream of abrasive over a predetermined limited arc including, a rotatably mounted rotor having a plurality of equally spaced circumferentially extending segments defining abrasive discharge passages therebetween, said segments each having a generally arcuate shaped inner end defining therebetween a central space of generally circular form, a rotatably mounted runner positioned within said central space having a plurality of equally spaced generally radially extending abrasive moving vanes differing in number from the number of discharge passages in said rotor, means for supplying abrasive to said runner vanes, and driving means operable to rotate said rotor and runner in timed relation and at speeds which are in inverse ratio to the number of discharge passages and abrasive moving vanes in said rotor and runner respectively so as to move successive runner vanes into discharging alignment with successive rotor passages at a predetermined clockdial position during rotation.

14. A centrifugal blasting machine operable to throw a concentrated stream of abrasive over a predetermined limiting arc including, a rotatably mounted rotor having a plurality of equally spaced radially arranged throwing blades extending inwardly short of the axis of rotation of said rotor to define a central space, a tubular sleeve extending into said space fixed to rotate with said blades, said sleeve having equally spaced abrasive discharge ports in the tubular side wall thereof adjacent the inner ends of said blades, a rotatably mounted control runner fitting within said sleeve comprising a plurality of equally spaced abrasive moving vanes differing in number from the number of discharge ports in said rotor sleeve, means for supplying abrasive to said runner vanes, and driving means operable to rotate said rotor and runner in timed relation and at speeds which are in inverse ratio to the number of discharge ports and abrasive moving vanes in said rotor and runner respectively so as to move successive runner vanes into discharging alignment with successive rotor passages at a predetermined clockdial position during rotation.

15. A centrifugal blasting machine operable to

throw a concentrated stream of abrasive over a predetermined limited arc including, a rotatably mounted rotor comprising spaced side wall members, a plurality of equally spaced blades supported by said side wall members extending inwardly short of the axis of rotation of said rotor defining a central space, a tubular sleeve having a discharge port for each of said blades rotating with said blades and extending into said central space, a control runner fitting within said rotor sleeve, said runner comprising equally spaced abrasive moving vanes extending inwardly short of the axis of rotation of said runner to define a central space, said runner vanes differing in number from the number of discharge ports in said rotor, means for supplying abrasive to the central space in said runner, and driving means operable to rotate said rotor and runner in timed relation and at speeds which are in inverse ratio to the number of discharge ports and abrasive moving vanes in said rotor and runner respectively so as to move successive runner vanes into discharging alignment with successive rotor ports at a predetermined clockdial position during rotation.

16. A centrifugal blasting machine operable to throw a concentrated stream of abrasive over a predetermined limited arc including, a rotatably mounted rotor having a plurality of equally spaced radially extending throwing blades ex-

tending inwardly short of the axis of rotation of said rotor to define a central space, a tubular sleeve extending into said space fixed to rotate with said blades, said sleeve having equally spaced abrasive passages in the tubular side wall thereof adjacent the inner ends of said blades, a rotatably mounted control runner fitting within said sleeve comprising a tubular member having equally spaced discharge ports in the tubular side wall thereof, vanes fixed to said rotor sleeve for piling abrasive received from the discharge ports of said tubular runner member between the discharge passages of said rotor sleeve, abrasive scraper vanes fixed to rotate with said tubular runner member having the outer ends thereof positioned to sweep the abrasive piles into the discharge passages of said rotor sleeve, said vanes differing in number from the number of discharge passages in said rotor sleeve, means for supplying abrasive to said tubular runner member, and driving means operable to rotate said rotor and runner in time relation and at speeds which are in inverse ratio to the number of discharge ports and vanes in said rotor and runner respectively so as to move successive runner vanes into discharging alignment with successive rotor passages at a predetermined clockdial position during rotation.

CHESTER E. UNGER.
